DESIGN FOR A TABLE

Earl C. Booth, Columbus, Ind., assignor to Noblitt-
Sparks Industries, Inc., Columbus, Ind., a cor-
poration of Indiana

Application March 27, 1941, Serial No. 99,922

Term of patent 7 years

To all whom it may concern:

Be it known that I, Earl C. Booth, a citizen of the United States, residing at Columbus, Bartholomew county, Indiana, have invented a new, original, and ornamental Design for a Table, of which the following is a specification, reference being had to the accompanying drawing, forming part thereof.

Figs. 1, 2, and 3 of the accompanying drawing are, respectively, top plan, side-elevational, and end-elevational views of a table embodying my design.

I claim:

The ornamental design for a table, as shown.

EARL C. BOOTH.
